UNITED STATES PATENT OFFICE

STANLEY M. KENERSON, OF SPRINGFIELD, MASSACHUSETTS, ASSIGNOR TO STANDARD ELECTRIC TIME COMPANY, OF SPRINGFIELD, MASSACHUSETTS, A CORPORATION OF CONNECTICUT

ELECTRIC SWITCH

Application filed September 13, 1928. Serial No. 305,808.

The subject matter of this invention is intended primarily for use by patients in hospitals to close a plurality of signal circuits (leading for example to a light over the door 5 of the patient's room, a light over the nurse's desk or in the diet kitchen, a buzzer at the nurse's desk, an annunicator at a suitable location, a light in the patient's room to indicate that the signals function properly, etc.), but in various aspects the invention may be 10 used in connection with one or more circuits for any purpose whatsoever. Objects of the invention are to provide a switch which is readily portable, which is neat and attractive 15 in appearance, which is simple and economical in construction, which is durable and efficient in use, which can be readily assembled and disassembled, and which is generally superior to switches of this general type as here- 20 tofore constructed.

For the purpose of illustrating the genus of the invention, concrete embodiments are illustrated in the accompanying drawings, in which:

Fig. 1 is a side elevation of the preferred embodiment;

Fig. 2 is a section on line 2—2 of Fig. 1;

Fig. 3 is an end view (looking from the bottom of Figs. 1 and 2) with one part of the casing removed;

Fig. 4 is a side elevation of the plunger of the switch, parts being shown in cross section;

Fig. 5 is an end view (looking from the top of Figs. 1 and 2) with the casing and the insulating disk removed;

Fig. 6 is an axial section of a modification, the casing being removed;

Fig. 7 is a section on line 7—7 of Fig. 6;

Fig. 8 is a front view of pull-chain modification;

Figs. 9 and 10 are sections on lines 9—9 and 10—10 respectively of Fig. 8; and

Fig. 11 is a view similar to Fig. 2 showing the switch of Figs. 9 and 10 applied to a portable casing for push-button operation instead of pull-chain control.

The particular embodiment of the invention shown in Figs. 1 to 5 comprises a casing formed in two parts 1 and 2, threaded to-

gether at 3, a base 4 of insulating material mounted in casing 1 by a peripheral flange clamped between the two casing parts with peripheral portions on opposite sides of the flange which telescope into the parts 1 and 2, 55 a pair of contacts 5 and 6 mounted on the rear (the top in Fig. 2) of the base 4, as shown in Figs. 2 and 5, four L-shaped contact springs 7, 8, 9 and 10 mounted at 7', 8', 9' and 10' on the front of the support 4, as shown in 60 Figs. 2 and 3, and a plunger 11 for actuating the spring contacts. As shown in Figs. 2 and 3, the insulating support 4 has a cylindrical extension on its rear face, portions of this extension being cut away to accommodate the 65 springs 5 and 6, thus dividing the extension into two parts 12 and 13 (Fig. 5). Resting on the face of this extension is an insulation disk 14 to hold the wires bunched in the end of the casing 1 away from the contacts 5 and 6, the wires extending to the various contacts either through perforations in the disk 14 or through notches in its periphery. 70

The plunger 7 comprises a circular piece of insulation 15 having a conducting ring 16 75 mounted in a circumferential groove near its forward end and having axial bores to receive the spring 17 and the metallic portions of the plunger comprising a head 18 projecting from the casing, a reduced portion 19 extending through the spring, a larger portion 20 projecting from the rear end of the insulation sleeve 15, and another reduced portion 21 projecting to the rear, a finger piece 22 being mounted on the reduced portion 21 and 80 projecting laterally toward or through a slot 23 in the casing 2. The parts 18, 19 and 20 slide freely but snugly in the insulation sleeve 15, the spring 17 normally holding the portions in the retracted position shown in Figs. 2 and 4. The portions 18, 19, 20 and 21 may be formed integrally with one another, or any two or more of these portions may be formed 85 separately and attached together and to the other portions in any suitable manner, as by threading or a pressed fit. The finger 22 may be welded or brazed in position, or attached by a pressed fit, or the portion 21 may be threaded into the portion 20 with a shoulder holding the finger 22 against the end of 90 100

the portion 20. The finger 22 may project through the casing, as shown in Fig. 2, so as to be actuated by the finger outside of the casing, or it may terminate short of the opening 22 so that an instrument must be inserted through the opening in order to actuate the finger.

The operation of the embodiment shown in Figs. 1 to 5, inclusive, is as follows: The parts normally stand in the position shown in Fig. 2, with all of the circuits open, the spring fingers 7, 8, 9 and 10 engaging the tapered portion 24 of the plunger to hold the plunger in the retracted position. When the plunger 11 is forced inwardly by pressure on the protruding portion 18, each of the spring contacts 7, 8, 9 and 10 contact with the ring 16 of the plunger, thereby closing the respective circuits through the ring 16. The plunger is then held in advanced position either by the friction of the spring contacts 7, 8, 9 and 10, or preferably by the contacts hooking over the ring 16 at their inclined portions 25 (Fig. 2). As shown in Fig. 2, the insulation base 4 may be provided on its forward face with a cylindrical extension 26 to engage the insulation sleeve 15 of the plunger and thereby limit the extent to which the insulation sleeve is advanced toward the rear, the cylindrical extension 26 being provided with a slot 27 to accommodate the finger 22. When the sleeve 15 reaches its innermost position, further pressure on the finger piece 18 causes the parts 18, 19, 20, 21 and 22 to advance still further, sliding in the cylinder 15, whereby the projection 21 engages the contact 6 and presses this contact against the contact 5. By making the spring 17 stiff enough to predominate over the springs 7, 8, 9 and 10, the circuits through the contacts 7, 8, 9 and 10 may be closed without closing the contacts 5 and 6; whereas, if the spring 17 is weaker than the springs 7, 8, 9 and 10, then the contacts 5 and 6 are necessarily closed when the circuit through 7, 8, 9 and 10 are initially closed. Thus, when using the switch 5-6 for operating a buzzer in a hospital system of the character above described, the tension of the springs may be so proportioned that the buzzer circuit is closed when the light circuits through 7, 8, 9 and 10 are initially closed, or so that the buzzer circuit may be closed at a later time by further pressure on the finger piece 18, as for example after getting no response to the light signals. As shown in Fig. 5 the contact 6 is held by the same rivet 10' which holds spring contact 10, thereby connecting the two contacts 6 and 10 together. When thus mounted the two contacts 6 and 10 are connected to a common battery lead, the other contacts 5, 7, 8 and 9 being connected to individual buzzer and light circuits respectively which ultimately connect with the other side of the battery. Thus when ring 16 contacts with

spring fingers 7, 8, 9 and 10 the light circuits connected to 8, 9 and 10 are closed through ring 16 to the common return connected to 6 and 10; and when contact 5 is pressed against contact 6 the buzzer circuit connected to 5 is closed through the common return connected to 6 and 10.

The modification shown in Figs. 6 and 7 is in general similar to the embodiment shown in Figs. 1 to 5, inclusive, corresponding parts being correspondingly designated. However, in this modification the plunger is provided with a cross bar 27 fast on a sleeve 30 which in turn is fast to the sleeve 15', the ends of the bar 7 having semi-cylindrical notches fitting over guide pins 26 mounted in the insulation support 4'. Portion 21' of the plunger has an integral flange 28 to act as a stop and an insulation tip 29 to engage spring 6'. In this form of the invention finger 22' is formed integrally with the bar 27.

The form of the invention shown in Figs. 8 to 11 inclusive is similar to the preceding forms, particularly that shown in Figs. 6 and 7, and in general comprises a circular base 31 of insulating material, a plunger 32 having an outer sleeve 33 of insulating material, and a plunger 34 reciprocating longitudinally in the sleeve 33 and normally held in extended position as shown in Fig. 9 by a spring, as illustrated in Fig. 6, the construction of the plunger 32 being the same as that shown in Figs. 6 and 7 except that the part 34 has an integral flange 35 and an annular groove 36. The L-shaped spring fingers 37 which contact with the metallic ring 39 when the plunger is moved inwardly to the position shown in Fig. 10 are mounted in radial recesses or grooves in the forward side of the base 31 in the same manner as illustrated in Fig. 7, that is, by terminal connectors in the form of rivets extending through the base. The contact 39 corresponding to 5' of Fig. 6 is in the form of a bar (Fig. 9) mounted at each end by eyelets 40 on the segmental raised portions of the base between the aforesaid grooves in which the spring fingers 37 are mounted; and the contact 41, corresponding to 6' of Fig. 6, is mounted under the base of one of the contact fingers 37 with its free end overlapping the bar 39 in spaced relation thereto, the circuit to which the contact 41 and the associated finger 37 are connected constituting the common return or the live wire for the other three contact fingers 37 and the contact bar 39. As in the preceding Fig. 6, the plunger has a tip 42 of insulating material which engages the contact 41 to press it against the contact 39 when the outer plunger 32 is fully advanced and the inner plunger 34 is also fully advanced in the outer plunger 32. Mounted on the inner end of the plunger 32 is a bar 42 (corresponding to bar 27 in Fig. 6) which has openings 120

to receive the guide pins 43 (Figs. 10 and 11). One end of this bar is extended as shown as shown at 44 in Figs. 10 and 11 to be engaged by the finger or a suitable instrument to retract the plunger to the normal open-circuit position shown in Fig. 9.

This form of the invention is adapted to be used either with a pull-chain 45, as shown in Figs. 8, 9 and 10, or without a pull-chain, in a manner similar to that described in connection with Figs. 1 to 7 inclusive, as shown in Fig. 9. When used without a pull-chain, as shown in Fig. 11, the plunger may be retracted either by pulling outwardly on the inner plunger 34 or pulling outwardly on the projection 44 fast to the outer plunger 32, the collar 46 serving to retract the outer plunger 32 when the inner plunger 34 is pulled outwardly.

When using that form of the invention shown in Figs. 8 to 11 inclusive in the manner shown in Fig. 11, the insulation base 31 has a peripheral flange mounted between the two casing parts 47 and 48 with the circuit conductors connected directly to the contact fingers or the rivets holding the contact-fingers on the base, a central recess 49 being provided on the rear face of the base 31 to accommodate the wires as they pass from the cable 50 to their respective terminals, grooves being provided in the rear face of the insulation base to connect the central recess with the marginal recesses containing the heads of the eyelets which secure the contact pieces on the base. In order to hold the cable 50 tightly to the base 31 a plate 51 and insulation washer 52 are perfectly mounted on the back of the base 31 by means of screws 53 which thread into the guide pins 43 and serve the further purpose of holding the guide pins on the front of the base. By making the cable opening in the disk 51 somewhat smaller than the outer diameter of the cable 50 and then, before attaching the disk 51 to the base, forcing the cable through the opening so that the covering of rubber or other compressible material is indented by the periphery of the opening with a portion projecting through the opening, this projecting portion of the cable covering is compressed longitudinally and caused to bulge out transversely, as shown in Fig. 11, when the plate 51 is forced to its seat by means of the screws 53, the bulging end of the cable covering being clamped tightly between the washer 52 and the bottom of the recess 49, as shown in Fig. 11.

When using this form of the invention in a junction box as shown in Figs. 8, 9 and 10 the disk 51 and washer 52 as well as the casting 47-48 are not used, the base 31 being mounted on the cover plate 54 of the junction box by means of a ring 55 closely surrounding the base 31 in front of the flange 56 and mounted on the cover plate of the junction

box by means of integral straps or legs 57, the base 31 being held in position in the ring 55 by means of a second ring 58 mounted on the ring 55 by means of screws 59. The conductors are connected to the respective contact fingers by means of angular terminal members 60 fastened in radial grooves in the rear face of the base 31 by means of screws 61 threaded into the rivet terminal connectors.

The means for actuating the plunger through the medium of a pull-chain, as illustrated in Figs. 9 and 10, comprises a bent lever 62 loosely mounted on the rear face of the plate 54 by means of a pin 63 so as to rock from the normal position shown in Fig. 9 to the position shown in Fig. 10 wherein the forked end 64 of the lever presses, through the medium of the flange 35, both plungers to their fully advanced positions wherein the fingers 37 hook over the ring 38 and the inner plunger 34 is advanced within the outer plunger 32 to engage the contact 41 and press it against the contact 39. As in the preceding embodiments contacts 39 and 41 may engage simultaneously with the engagement of the four contacts 37 with ring 38 or subsequently thereto, depending upon the strength of the coil spring between the two plungers 33 and 34 relatively to the strength of springs 37; also the inner plunger 34 is automatically retracted in the outer plunger 33 when the chain is released, the outer plunger being retracted only by pulling outwardly on the protruding portion 36 of the inner plunger 34.

When using the pull-chain embodiment of the invention with signal circuits for hospitals the advance of the outer plunger until the ring 38 interconnects the four spring fingers 37 may be used to light three signal lamps at suitable locations and the further advance of the inner plunger 34 within the outer plunger 32 may be used to close a buzzer circuit through the contacts 39 and 41 as in the preceding embodiments.

While the outer and inner plungers are hereinafter referred to as the main and auxiliary plungers respectively, it will be understood that the outer plunger might be used as an auxiliary plunger and the inner plunger as a main plunger; also that the switches may be arranged to open circuit or otherwise modify circuit connections, instead of closing circuit, when the plungers are advanced inwardly or to the rear; that means other than a coil spring may be used automatically to retract the one plunger relatively to the other; that means other than the fingers 7-10 or 7'-10' or 37 may be employed for holding the main or outer plunger in advanced position; that the spring means typified by the coil spring may be interposed between the plunger or actuators so that the plungers will move together in response to force applied to the main instead of the auxiliary plunger in

which case the auxiliary switch would of course be positioned to function before the main switch or switches; that the two plungers or actuators may be slidably or movably interconnected otherwise than by telescoping together; that the plungers reciprocate along a line intersecting the insulation base, the two plungers and circular base preferably being coaxial; and that many other modifications may be made within the scope of the appended claims.

I claim:

1. An electrical switch comprising a plurality of plungers reciprocable relatively to each other, a switch cooperating with one plunger when the plunger is actuated, a switch cooperating with the other plunger when it is reciprocated relatively to the first plunger, and means for indefinitely holding one plunger in operative position while the other plunger is in inoperative position.

2. An electrical switch comprising main and auxiliary actuators movable together and relatively to each other, a spring normally holding the auxiliary actuator retracted relatively to the main actuator, a switch responsive to actuation of the main actuator, another switch responsive to advance of the auxiliary actuator relatively to the main actuator against the action of said spring and means for actuating one plunger independently of the other.

3. An electrical switch comprising inner and outer plungers telescoped together, a plurality of contacts cooperating with the outer plunger to modify a circuit when the outer plunger is actuated, a plurality of other contacts cooperating with the inner plunger to modify a circuit when the inner plunger is moved relatively to the outer plunger, and manual means for moving one plunger to circuit-modifying position without moving the other plunger.

4. An electrical switch comprising a plurality of plungers reciprocable relatively to each other, a switch cooperating with one plunger when the plunger is actuated, a switch cooperating with the other plunger when it is reciprocated relatively to the first plunger, means for automatically retracting the second plunger relatively to the first plunger without retracting the first plunger.

5. An electrical switch comprising main and auxiliary actuators movable together and relatively to each other, a spring normally holding the auxiliary actuator retracted relatively to the main actuator, a switch responsive to actuation of the main actuator, another switch responsive to advance of the auxiliary actuator relatively to the main actuator against the action of said spring, and means for holding the main actuator in advance position while permitting the auxiliary actuator to retract relatively to the main actuator.

6. An electrical switch comprising main and auxiliary actuators movable together in response to a force applied to the auxiliary actuator and the auxiliary actuator having further movement relatively to the main actuator in response to such force, and a spring interposed between the two actuators for normally holding the auxiliary actuator retracted relatively to the main actuator.

7. An electrical switch comprising inner and outer plungers slidably telescoped together, a spring normally holding one plunger retracted relatively to the other plunger, a switch responsive to advance of the latter plunger, and another switch responsive to further advance of the first plunger against the action of said spring.

8. An electrical switch comprising inner and outer plungers slidably telescoped together, a spring normally holding one plunger retracted relatively to the other plunger, a switch responsive to advance of the latter plunger, another switch responsive to further advance of the first plunger against the action of said spring, a face plate supporting said plungers therebehind to reciprocate forwardly and rearwardly, a pull extending through an opening in the plate, and means interconnecting said pull and plungers behind the plate to reciprocate the plungers rearwardly when the pull is pulled forwardly.

9. An electrical switch comprising a face plate, a plunger mounted behind said plate to reciprocate forwardly and rearwardly relatively to said plate, a pull extending through an opening in the plate, and means interconnecting said pull and plunger behind the plate to reciprocate the plunger rearwardly when the pull is pulled forwardly.

10. An electrical switch comprising a face plate, a plunger mounted behind said plate to reciprocate forwardly and rearwardly relatively to said plate, a pull extending through an opening in the plate, and a lever interconnecting said pull and plunger behind the plate to reciprocate the plunger rearwardly when the pull is pulled forwardly.

11. An electrical switch comprising a face plate, a plunger mounted behind said plate to reciprocate forwardly and rearwardly relatively to said plate, a pull extending through an opening in the plate, and means interconnecting said pull and plunger behind the plate to reciprocate the plunger rearwardly when the pull is pulled forwardly, said plunger having a portion projecting through an opening in the plate for reciprocating the plunger forwardly.

12. An electrical switch comprising a face plate, a plunger mounted behind the plate to reciprocate forwardly and rearwardly relatively to the plate, a pull extending through an opening in the plate to reciprocate the plunger, an insulation base having a peripheral flange, and a base support having parts

clamping said flange therebetween, one of said parts having legs straddling said plunger and attached to the back of said face plate.

13. An electrical switch comprising a base of insulation material having a peripheral flange, a base support having parts clamping said flange therebetween, switch contacts mounted on the base, and a plunger extending through an opening in said support for actuating said contacts.

14. An electrical switch comprising a base of insulation material having a peripheral flange, a base support having parts clamping said flange therebetween, switch contacts mounted on the base and a plunger extending through an opening in said support for actuating said contacts, said flange being intermediate the ends of the base so that the peripheral portions of the base on opposite sides of the flanges extend into said parts respectively.

15. An electrical switch comprising a base of insulation material having a peripheral flange, a base support having parts clamping said flange therebetween, L-shaped switch contacts mounted on the front of the base, a plunger engaging said contacts, and terminal connections extending through the base for attachment to circuit conductors.

16. An electrical switch comprising an insulation base, a plunger reciprocating toward and from the base, L-shaped switch contacts mounted on the front of the base for engagement with the plunger, and terminal connectors extending through the base for attachment to circuit conductors at the rear of the base.

17. An electrical switch comprising an insulation base, a plunger reciprocating along a line intersecting the plane of the base, the base having recesses extending radially of said line, circuit connections mounted in said recesses, and plunger engaging switch contacts mounted on the base in circuit with said connectors respectively.

18. An electrical switch comprising an insulation base, a plunger reciprocating along a line intersecting the plane of the base, the base having superposed radial recesses on its front and rear surfaces respectively, switch contacts mounted in the front recesses for engagement with said plunger, and circuit connectors mounted in the rear recesses in electrical communication with said contacts respectively.

Signed by me at Boston, Massachusetts,
this fifth day of September, 1928.

STANLEY M. KENERSON.
